UNITED STATES PATENT OFFICE.

THEODORE F. TIMBY, OF BROOKLYN, NEW YORK.

SIFTER.

SPECIFICATION forming part of Letters Patent No. 331,344, dated December 1, 1885.

Application filed September 20, 1884. Serial No. 143,562. (No model.)

To all whom it may concern:

Be it known that I, THEODORE F. TIMBY, a citizen of the United States, residing at Brooklyn, in the State of New York, have invented 5 a new and useful Improvement in Sifters, of which the following is a specification.

This invention relates, as an improvement, to that class of sifters for domestic use in which rotary agitators are employed to effect the 10 passage of the fine particles of flour, sugar, &c., separated from lumps and foreign particles, through wire screens or sieves, and in which the sifters are adapted to be used as scoops, so as to be readily filled, and also as 15 measures, so as to indicate the quantities taken up thereby, and thus facilitate sifting given exact quantities into mixing-pans, for example, in a convenient manner.

The present invention consists in an im- 20 proved sifter of said class embodying certain novel features of construction, hereinafter described and claimed.

A sheet of drawings accompanies this speci- 25 fication as part thereof.

Figure 1 of these drawings is a perspective view of my improved sifter. Fig. 2 represents a vertical section of the same, and Fig. 3 represents a horizontal section on the line 3 3, Fig. 2, illustrating the sifting operation. 30 Like letters of reference indicate corresponding parts in the several figures.

This sifter is composed of an upright cylindrical body, A, of tin, (tin-plate,) a flat sieve-bottom, B, of tinned wire-cloth, and an axial rotary agitator, C, of tinned wire, as its main parts, together with a handle, h, for the body, and a ring, r, which re-enforces and finishes the lower edge of the body and stretches and secures the sieve-bottom, both 35 made of scraps of the tin, so that the tin for two sifters may be taken from a single commercial sheet of tin-plate, a small annular disk, s, of tin, flat, soldered to the sieve-bottom at its middle to form a step-bearing for 40 the lower pivot of the agitator, and a dished one, c, soldered on the stem of the agitator as its collar, a small loose knob, k, of wood or pewter, for the upper end of the agitator-stem, and a pair of tinned-iron bent wires, a b, which 45 together form a combined upper bearing unfastening device and pressure-regulator for 50

the agitator, and also stiffen the handle h, in the edges of which their outer ends are held, as aforesaid.

The body A is preferably cut with the cus- 55 tomary upward extension or lip, l, at its upper edge, to facilitate its use as a scoop, as aforesaid, and provided with the customary graduating-beads, g, to adapt it to measure different quantities. A bead, f, parallel to said 60 graduating-beads, forms an upper bearing for and a tight joint around the sieve-bottom B, and insures the correct location of the latter in the body relative to said graduating-beads.

The flat sieve-bottom is cut from a minimum 65 of the relatively expensive wire-cloth, and is readily stretched and kept clean, so as to be highly effective. It is cut with a depending marginal rim, within which the ring r is placed, after which both are forced into place 70 within the body. The lower edge of the ring is then turned up around the lower edge of the body, as shown in Fig. 2, to securely unite the parts and finish this edge of the sifter.

The sieve-bottom is provided with the cen- 75 tral step-bearing, s, and is punched within the same before its insertion in the body, and after the handle h is attached, with the outer ends of the wires a b fast therein, their inner ends having been previously shaped as shown, the 80 body is ready to receive the agitator C. The inner extremities of the wires a b are in the form of half-rings, each embracing the stem of the agitator when the latter is in place on that side opposite the wire end which is fast 85 in the handle, as clearly seen in Fig. 1; consequently by pressing the wires together at a point between their inner ends and the handle said half-rings are separated and the agitator is released, and so released it is withdrawable 90 through the open upper end of the body as one part, its lower pivot lifting freely from said step-bearing s. The upper bearing formed by said wires a b is immediately above said collar c, as seen in Fig. 2, and conse- 95 quently, by slightly bending the wires vertically, the pressure of the agitator on the sieve-bottom may be readily increased or diminished.

The agitator C, excepting its collar c and 100 knob k, is made from a single piece of wire, bent as shown in Figs. 2 and 3—that is to say,

beginning with its straight lower pivot, the wire is bent at right angles and rebent in this plane to form three (more or less) horizontal wings, and, returning to the center, is interlocked with the pivot end and carried upward in line with the latter to the proper point for the first crank-bend, beyond which another crank-bend is formed simultaneously with the first, followed by fastening on said collar and 10 knob by means of solder. The interlocking of the stem with the pivot end may also be made tight by soldering; but this is not considered essential.

By making the agitator of the peculiar shape 15 represented in Figs. 2 and 3—that is to say, with horizontal skeleton wings of clover-leaf shape—the agitator is adapted to operate, when rotated in either direction, in the manner represented by Fig. 3, the outer front edge of 20 each wing carrying the particles with which it comes in contact outward, while the inner front edge of each wing carries the particles with which it comes in contact inward. Lumps are thus carried back and forth over the 25 surface of the flat sieve-bottom until they are pulverized ordinarily, while lighter foreign particles are collected in the small central space indicated by a dotted circle in Fig. 3, where the mass is comparatively motionless. Moreover, agitation is confined to the particles 30 immediately overlying the sieve-bottom, where alone it is effective, and there is no grinding action.

I have specified in detail the construction 35 of my improved sifter, but do not wish to confine my respective claims, hereinafter stated, to mechanical details which are not essential to the respective features of the invention, as claimed.

Having thus described my said improvement in sifters, I claim as my invention and desire to patent under this specification—

1. The combination, in a sifter, of an upright circular body, a flat sieve-bottom having a central step-bearing, a rotary agitator having a pivot at its lower end, a hand-crank at the upper end of its vertical stem, and a collar 45 below said crank, and an upper bearing for

said agitator, adapted to embrace said stem above said collar and to be opened to release 50 the agitator, substantially as herein specified.

2. The combination, in a sifter, of an upright circular body having a sheet-metal handle on one side thereof, a sieve-bottom within the lower part of said body, an axial rotary 55 agitator, and a wire or wires applied to said handle as stiffening-wires, and extending inwardly from the upper end thereof to support the agitator, substantially as herein specified.

3. The combination, in a sifter, of an upright circular body having a sheet-metal handle on one side thereof, a flat sieve-bottom secured within the lower part of said body, an axial rotary agitator having its stem provided with a collar, and a combined upper bearing 65 unfastening device and pressure-regulator for the agitator, formed by a pair of wires, the inner ends of which embrace said stem above said collar, while their outer ends are held within the respective edges of said handle and 70 serve to stiffen the latter, substantially as herein specified.

4. The combination, in a sifter, of an upright circular body, a flat sieve-bottom secured within the lower part of said body and provided with a central step-bearing, and an axial 75 rotary agitator having a lower pivot, a series of horizontal skeleton wings of clover-leaf shape immediately above said bottom, a vertical stem, and a crank at the upper end of the 80 latter formed of a single continuous wire, substantially as herein specified.

5. The combination, in a sifter, substantially as herein specified, of an upright circular body, a flat sieve-bottom, and an axial rotary agitator having a lower pivot, a series of horizontal skeleton wings of clover-leaf shape immediately above said bottom, and a central 85 open space around said pivot, in which light foreign matters are collected in operation, in 90 the manner set forth.

THEODORE F. TIMBY.
